UNITED STATES PATENT OFFICE.

CLIFFORD M. LEONARD, OF CHICAGO, ILLINOIS.

REINFORCED-CONCRETE BUILDING.

1,128,011.

Specification of Letters Patent.

Patented Feb. 9, 1915.

Application filed April 30, 1909. Serial No. 493,147.

To all whom it may concern:

Be it known that I, CLIFFORD M. LEONARD, a citizen of the United States, and resident of Chicago, county of Cook, and State of Illinois, have invented certain new and useful Improvements in Reinforced-Concrete Buildings, of which the following is a specification, and which are illustrated in the accompanying drawings, forming a part thereof.

The invention relates to buildings wherein the floor and supporting columns therefor are constructed from reinforced concrete.

More particularly, the invention relates to an improved manner of reinforcing the said columns and the floor slabs mounted thereon.

The object of the invention is to provide a building construction of the type described having the reinforcing members of its supporting columns and floor slabs so associated as to effect an integral connection between these parts, the reinforcing members being of such form that they may be readily and entirely produced without special tools from the rods and bars now in common use for reinforcing concrete structures.

In the accompanying drawings, Figure 1 is a plan view of a detail of building construction embodying the features of the invention, some of the parts being broken away to illustrate the manner of reinforcing a floor slab and supporting column therefor; Fig. 2 shows in perspective the parts illustrated in Fig. 1.

A plurality of upright steel rods 10 are employed as reinforcing members of the floor-supporting columns, as 11, of a building. Most desirably the column 11 has a flaring head 12. In order that this flaring head may be as effectively reinforced as the body of the column, each of the rods 10 is bent outwardly adjacent its higher end, as indicated at 13, Fig. 2. As shown, the rods 10 are symmetrically disposed about the axis of the column and each is located adjacent the periphery or surface of the column. By bending the rods 10 outwardly at 13 these rods may be brought as near to the surface of the column in the flaring head 12 as in the body of the column.

A plurality of closed hoops 14, surround and connect the vertical reinforcing rods 10. These hoops are spaced or located at intervals throughout the length of the column, those located within the head of the column

being of sufficient diameter to surround the outwardly-turned portions of the rods 10.

A floor slab 15 is illustrated as being mounted upon the head of column 11, and reinforcing members 16 extend from the head of the column outwardly into the floor slab in various directions. As shown, the reinforcing members 16 are laid upon the hoop 14 at the top of the column 11, preferably in such a way that they extend diametrically across the hoop and project beyond the column head at each end, as at 17, 18 (Fig. 2). To provide for the intersection of the reinforcing rods 16 at the axis of the column 11, the mid-portion of certain of these rods is bent downwardly, as shown at 19, one of the rods, as 20, being preferably straight intermediate the points where it lies upon the hoop 14, and the corresponding portions of the other rods being deflected downwardly in differing amounts, each rod being deflected sufficiently to pass beneath the rod 20 and those other rods whose mid-portions are deflected to a less extent.

Most desirably the ends, as 17, 18, of the rods, as 16, which project beyond the head of the column 11 are bent downwardly, and upon these downwardly-deflected projecting ends of the rods 16 a plurality of rectangular open frames 21, 22, are laid. Preferably the angles, as 23, 24, of the frames 21, 22, extend in different directions with respect to the axis of the column 11, the frame 21, as shown, being of less diameter than the frame 22, and being laid upon the rods 16 with each of its angles located midway between adjacent angles of the frame 22. By means of the rods 16 and frames 21, 22, a table, having its margins inclined downwardly, is provided upon the head of the column 11. This table conveniently serves for supporting such reinforcing material as may be employed for extending through the floor slab 15 from the column 11 to adjacent columns, not shown. As shown, a plurality of sets of parallel rods, as 25, 26, 27, 28, are employed for this purpose. Preferably the rods of each of these sets are laid upon the table formed by the rods 16 and frames 21, 22, in such a way as to extend outwardly from the column 11 into the floor slab in a plurality of different directions symmetrically disposed about the column.

By forming the rods 16 of the floor slab independent of the vertical rods 10 of the

column 13, the floor may be reinforced to any desired degree, irrespective of the size or strength of the supporting column.

The construction described provides an efficient manner of constructing buildings having floors supported by columns without the use of girders extending from column to column and beams between the girders. Such a floor may be made of uniform thickness throughout its entire extent and is commonly termed a flat floor slab.

I claim as my invention—

In a reinforced concrete building, the combination, with a concrete column having a flaring head, and a flat floor slab, formed integrally therewith, of a series of symmetrically spaced vertical continuous rods extending through the column adjacent to its periphery and having their upper ends bent outwardly to correspond to the flare of the col-

umn head, a series of spaced closed hoops in said column and head surrounding said rods, the hoops in the head being progressively of greater diameter from the bottom to the top of the head, a plurality of substantially horizontal reinforcing rods extending through the floor slab and over the column, and a table, for supporting the horizontal rods of the floor slab, comprising a plurality of independent horizontal rods seated on the upper hoop of the column, and diametrically arranged at different angles with respect to the axis of the column and extended into the floor slab beyond the column in opposite directions.

CLIFFORD M. LEONARD.
